UNITED STATES PATENT OFFICE.

OTTO ZIMMERMANN, OF LUDWIGSHAFEN-ON-THE-RHINE, GERMANY.

DRYING APPARATUS.

Application filed March 28, 1921. Serial No. 456,201.

To all whom it may concern:

Be it known that I, OTTO ZIMMERMANN, a citizen of the Republic of Germany, residing at Ludwigshafen-on-the-Rhine, Germany, have invented certain new and useful Improvements in Drying Apparatus (for which I have filed applications in Germany March 8th, 1918, and August 2nd, 1919, in Austria, August 15th, 1919, in Hungary, April 4th, 1918, and in Great Britain March 10th, 1920), of which the following is a specification.

This invention relates to an apparatus for drying potatoes, turnips, grain, fruit, mushrooms, fodder, kitchen and slaughter-house waste, fish, mussels, as well as textiles, brown-coal, peat, chemical products and the like by means of air heated through the medium of steam or combustion gases and forced through the drying chambers by means of a fan or the like.

The object of the invention is to produce a drying apparatus which can easily be fitted up in any existing building, and the invention consists in the provision of two drying chambers arranged at opposite sides of two parallel flues which communicate at one end with a heat source and at the other end with a chimney, means being provided for working the chambers either partly or together and for reversing the direction in which the air passes through the drying floors.

Fig. 1 of the drawings represents a diagrammatic front view of the apparatus,

Fig. 2, a plan of the same including the heat source and the fan, and

Fig. 3, a side view including the fan.

The air may be heated by means of a coke oven 21 and forced by a fan 22 into a pipe 23 communicating with two parallel flues 24 and 27. A door *a* can be adjusted for cutting off the communication with either of the two flues. Two drying chambers 25 and 26 are arranged one at each side of the flues. The flue 24 communicates with the lower part of the drying chamber 25, and the flue 27, with the lower part of the chamber 26. The drying chambers contain drying floors 30 and are covered by a superstructure 29 which is preferably made of wood and which may be comparatively higher than shown in the drawings. The chambers are supported on planks 31. 28 is a chimney flue which contains a flap *d* wherewith its communication with the su-

perstructure can be interrupted. A door *e* shuts off the communication of the chimney flue with either of the flues 24 or 27, and flaps *b* and *c* enable the superstructure to be set into communication either with one another or with the flue 28.

The working of the apparatus may be carried out in the following manner:

(a) The air can be led from the flue 23 into the chamber 25 and thence into the superstructure and past flaps *b* and *d* into the chimney, the flap *a* being closed against the flue 27, the flap *e*, against the flue 24, and the flap *c* against the right-hand part of the superstructure. Thus the drying can be commenced in the chamber 25 while the chamber 26 is being emptied and refilled.

(b) The chamber 26 having been refilled, the flap *d* can be closed against the superstructure, and the flap *c* opened so that the air, having passed upwards through the materials in the chamber 25, is led into the right-hand part of the superstructure whence it passes downwards through the materials in this chamber and is discharged through the flue 27 into the chimney.

(c) When the materials in the chamber 25 are dry, the flaps *a* and *e* are reversed for shutting off the hot air from this chamber and leading it upwards through the chamber 26 into the chimney flue, the flap *d* being reopened and the flap *b* closed.

(d) The chamber 25 having been cleared and refilled, the hot air from the chamber 26 is led through the superstructure and downwards through the wet materials in the chamber 25 whence it passes into the chimney.

From this procedure it follows that each fresh charge is first exposed to a current of slightly moist air coming from the neighbouring chamber and passing through the materials in a downward direction. After this preliminary drying, the process is continued and finished by dry hot air passing upwards through the materials. Owing to this reversal of the current, a turning over of the materials will in most cases be obviated. An important advantage of the arrangement is the continuous working, there being no need for interrupting the heating or for wasting the heat. The air passing finally through a fresh wet charge of materials, it will be completely saturated, and the heat will be utilized to the full extent. A further advantage is that the saturated

air can be discharged into the chimney without coming into contact with any other working chamber.

I claim:—

- 5 A drying apparatus of the character described, comprising the combination with a heat source of two parallel flues communicating at one end with said heat source, a chimney communicating with the opposite 10 end of the flues, two drying chambers arranged at opposite sides of the flues, drying floors arranged in said chambers, the space below the drying floors of both chambers being in communication with the adjacent flue, a superstructure covering the two 15 chambers and communicating therewith, means for setting the two parts of the superstructure in communication either with one another or with the chimney, means for interrupting the communication of 20 either flue with the heat source, and means for interrupting the communication of either flue with the chimney, substantially as and for the purpose set forth.

DR. OTTO ZIMMERMANN.
